UNITED STATES PATENT OFFICE

EARL E. BERRY AND THEODORE C. ROBERTS, OF BELOIT, WISCONSIN, ASSIGNEES TO
BELOIT IRON WORKS, OF BELOIT, WISCONSIN, A CORPORATION OF WISCONSIN

METHOD OF AND APPARATUS FOR MAKING PAPER

Application filed June 27, 1931. Serial No. 547,215.

This invention relates to a method of and apparatus for making paper and more particularly to the use of a resilient covered suction roll as a pressure or transfer roll, more especially in connection with the manufacture of tissue or other light weight papers.

It has heretofore been customary in the manufacture of paper, and more particularly in the manufacture of tissue or other light weight paper, to use a pick-up type of felt for transferring the paper web from the forming part of the machine to a transfer roll or directly by means of a pressure roll to a drying cylinder. Ordinarily, light weight papers are made upon either a Yankee or Harper Fourdrinier, or upon a cylinder machine. The Yankee machine is used for making what is known as machine glazed, or M. G., paper and is equipped either with a Fourdrinier forming portion or a cylinder. In either case, a pick-up type of felt carries the moist web of paper from the forming portion to the single large drier that is characteristic of this type of machine. Where the machine is equipped with a plain bottom couch, the top felt passes between the top couch and the bottom couch to lift the sheet from the wire and then carries the wet web of paper on through the presses and passes between a pressure roll and the drying cylinder, the pressure roll serving to transfer the web of paper from the felt to the surface of the drier. Such a machine necessarily has to be equipped with a bottom felt in order to get the sheets through the presses but after passing through the bottom felt parts from the top felt and leaves the sheet adhering to the top felt.

In a Harper Fourdrinier machine, equipped with a plain bottom couch, it is customary for the top felt to pass under the top couch to pick up the moist web of paper from the forming wire and carry it back over the forming portion of the machine to a transfer roll, where, by means of a pressure roll, the web of paper is transferred from the felt to the transfer roll and then picked up from the transfer roll and carried over into the driers.

The arrangement of a cylinder machine is often quite similar, with the pick-up felt car-

rying the web of paper either to a transfer roll or directly to the drier cylinder, with a pressure roll to effect the transfer of the web from the felt to the transfer roll or to the surface of the drier.

In all of these various arrangements, trouble may be, and frequently is, experienced in transferring the moist web of paper from the pick-up felt, or top felt, to the transfer roll or to the surface of the drier drum. Not infrequently, the trouble is occasioned by crushing at the nip of the pressure roll and transfer roll, or drier drum, due to the piling up of water that has been squeezed from the sheet in back of the nip between the two rolls. As is well known to those skilled in the art, this condition results in a crushing of the wet web of paper and also leaves the web wetter than it should be at this point.

The present invention contemplates the correction of the improper conditions referred to by the use of a suction pressure roll to suck the nip dry and eliminate the crushing. The use of the suction roll at this point, furthermore, greatly lengthens the life of the pick-up felt, since it prevents the felt from "filling up", an effect that has heretofore commonly resulted from the crushing at the nip. A suction pressure roll at this point also has the added advantage of producing a drier sheet.

Where the suction roll of our invention is used as a pressure and transfer roll for transferring the wet web of paper directly to the large drying cylinder of a Yankee machine, we find that the efficiency of the suction roll is much greater than when a suction press roll is used in the customary way in conjunction with a plain top press roll. This greater efficiency is doubtless due to the fact that when the wet sheet is applied at high pressure against the heated surface, there is an instantaneous transfer of heat from the drier to the sheet of paper that materially lowers the viscosity of the water in the sheet and thereby causes the paper fibers to give up their water more freely than in the usual arrangement of a suction press roll cooperating with an unheated top roll.

Moreover, the use of a suction pressure roll

- as indicated in connection with a Yankee drier, makes it possible to eliminate the bottom felt which is ordinarily used with this type of machine. Since the bottom felt on the usual Yankee machine has a very short life, usually lasting only from 5 to 8 days and costing from \$200.00 to \$350.00, its elimination alone means a tremendously large saving.
- It is therefore an object of this invention to provide a novel means and method for making paper, and more particularly light weight paper, on types of paper making machines that require the use of a pick-up felt.

It is a further important object of this invention to provide a novel and improved construction of suction roll for use as a pressure and transfer roll in the manufacture more particularly of light weight papers.

It is a further important object of this invention to provide a resilient covered suction pressure roll for cooperation with the pick-up felt of a paper machine for transferring the wet web of paper from the felt to a transfer roll or to a heated drier cylinder.

It is a further object of this invention to provide a novel combination of means including a resilient suction roll in connection with the manufacture of light weight papers and tissues that eliminates the necessity of using a bottom felt.

Other and further important objects of this invention will be apparent from the disclosures in the specification and the accompanying drawings.

This invention (in a preferred form) is illustrated in the drawings and hereinafter more fully described.

On the drawings:

Figure 1 is a diagrammatic view of a cylinder type of Yankee machine equipped with a suction press roll of our invention.

Figure 2 is a sectional view of the suction pressure roll of our invention.

Figure 3 is a diagrammatic view of the Fourdrinier type of Yankee machine equipped with a suction pressure roll.

Figure 4 is a diagrammatic view illustrating the use of a suction pressure roll on a Harper Fourdrinier machine having a creping attachment.

As shown on the drawings:

The reference numeral 1 indicates a cylinder vat of usual construction having a forming mold or cylinder 2 therein. In a manner well known to those skilled in the art, the web of paper formed on the cylinder mold 2 is transferred by means of a couch roll 40 to a felt 4. Said felt 4 carries the wet web of paper into the nip between a drying cylinder 5 and a pressure roll 6, which latter roll effects the transfer of the web of paper from the felt to the surface of the drier drum. As illus-

trated in Fig. 1, the drier cylinder 5 constitutes the usual, large diameter drier of a Yankee machine.

In accordance with our invention, the pressure roll 6 is a suction type of roll, preferably of the novel and improved construction shown in Figure 2. Said roll comprises a perforated metal shell 10 having an inner, longitudinally extending suction chamber 7 connected at one or both ends to a suitable source of suction (not shown). Said chamber 7 is provided with a pair of spaced flanges 41 extending substantially the full length of the chamber and thereby providing an opening 8 from the interior of the chamber radially directed toward the inner surface of the shell 10. A floating head 9, mounted from said flanges 41, is provided with lengthwise extending packing strips 42 and end packing strips 43 that are pressed against the inner surface of the shell 10 in a manner described and claimed in the U. S. patent to Berry No. 1,679,598 issued August 7th, 1928.

Up to this point, it will be understood that the construction of the suction pressure roll 6 may be either as described or may be modified in accordance with well known practice, since the specific features of construction thus far described form no part of the present invention.

The usual type of metal suction roll cannot, however, be successfully used for the purposes of this invention insofar as it applies to the making of light weight and tissue papers on the types of paper making machines herein shown and later described. If the usual perforated metal suction roll were used in place of the suction pressure roll 6 of our invention, inequalities of pressure would be unavoidable due to the impossibility of accurately grinding the surfaces of the metal suction roll and the drier drum or other metal roll to which the web of paper is to be transferred. Consequently, it would be impractical, if not impossible, to employ the usual type of metal suction roll in connection with the manufacture of tissue and other light weight papers for the purposes herein set forth.

Accordingly, the suction pressure roll of our invention is provided with a resilient covering 12 made of some suitable cushioning material, preferably rubber. Said resilient covering 12 is suitably in the form of a continuous sleeve of rubber of appropriate density, such as that of the usual rubber covered press roll. The rubber sleeve is secured to the outer surface of the shell 10 in any suitable manner, as by vulcanizing, cementing or by the so called Vulcalock process. After assembly of the sleeve 12 upon the shell, corresponding perforations 13 in the sleeve are made to those in the shell 10, or, the assembled composite shell is drilled to form the perforations 11 and 13 at the same

time or the shell may be perforated before assembly and a correspondingly perforated sleeve applied thereto.

With a suction pressure roll such as described, positioned as at 6 in the paper making machine diagrammatically shown in Figure 1, said roll serves both as a suction roll to remove water from the wet web of paper on the felt 4 and also as a pressure and transfer roll to transfer the web of paper to the surface of the large drying cylinder 5. The suction opening 8 is preferably directed against the web a slight distance in advance of the nip of the rolls so that the web is acted upon by the suction before being pressed between the roll and drum. This action aids in the subsequent delivery of the web by the felt to the drier drum. The provision of the resilient covering or shell 12 eliminates any tendency to crush the sheet as it passes into the nip between the roll 6 and the drying cylinder 5.

As previously pointed out, the use of a suction roll at this point, coacting with the heated drier cylinder, not only sucks the nip dry but also results in greatly improved efficiencies over the use of the usual type of suction press roll in association with a plain, unheated top roll. The heat from the drying cylinder 5 instantly heats the water contained in the web of paper pressed in contact therewith by the suction roll 6 and thereby reduces the viscosity of the water to such an extent that it is pulled much more readily through the web of paper and accompanying felt by the suction action of the roll 6 than would be the case were the web not heated while being acted upon by the suction roll.

In Figure 1 there is also shown a second suction roll, indicated by the reference numeral 6a, ahead of the suction roll 6 for effecting a preliminary removal of water from the felt and web carried thereon. The suction roll 6 may be of standard construction and need not have a resilient covering such as the suction pressure roll 6 of our invention.

In Figure 3 there is illustrated diagrammatically a Fourdrinier type of Yankee paper machine comprising a Fourdrinier forming portion 16 having the usual endless forming wire 15 associated therewith. Stock flows from the head box 14 onto the forming wire 15 and passes over the usual table rolls and suction boxes to the couch end of the table structure. As the partially formed web of paper on the wire 15 passes over a lower couch roll 19, a top felt 18 is brought into contact with said web of paper by means of an upper couch to pick up the web from the wire. The top felt 18 is trained around the usual rollers 20 so as to come into contact with the large drying cylinder 21. A suction pressure and transfer roll 22 of similar construction to that shown in Figure 2 and above described, is so mounted as

to press the felt 18 against the surface of the drier drum 21 and effect the transfer of the web of paper from the felt to the surface of the drier drum. The functions of the suction pressure roll 22 are the same as those already described above.

In Figure 4 there is shown a Harper type of Fourdrinier paper making machine, indicated generally by the reference numeral 44. A top felt 45, coacting with a top couch 46, picks up the web of paper from the forming wire 47 as it passes around the lower couch roll 48. As is characteristic of this type of machine, the top felt 45 extends back over the forming wire 47 and serves to carry the web of paper, in the installation illustrated, to a heated cylinder 49 with which is associated a creping doctor 33. A suction pressure roll 24, of the same construction as that above described, serves to transfer the wet web of paper from the top felt 45 to the surface of the heated cylinder 49. Rotation of the cylinder 49 carries the web of paper up against the creping doctor 33, by means of which the paper is given the desired creped effect. From the creping doctor 33, the creped, still moist web of paper is carried over into the nip between the bottom drier felt 50 and the first bottom drier drum 51 of the drier section 25.

It will be noted that each of the various types of paper making machines illustrated herein are particularly adapted for the manufacture of tissue or other light weight papers and it is in connection with these types of machines that the resilient covered suction pressure roll of our invention finds its greatest utility.

In the preferred embodiment of our invention, the resilient covered suction pressure roll has been more particularly described in connection with its use as a pressure and transfer roll for removing water from a moist paper web as carried on a pick-up type of felt, or top felt, and for transferring the paper web from the felt to a heated drying cylinder. In such an arrangement, suction pressure rolls of our invention have peculiar utility in that they provide improved means for transferring the paper from the felt to the drying cylinder and also for removing water from the paper web. The elimination of the use of a bottom felt, as is ordinarily necessary in this type of installation, constitutes in itself a considerable saving which results directly from the use of suction pressure rolls of our invention.

We are aware that many changes may be made and numerous details of construction may be varied through a wide range without departing from the principles of this invention, and we, therefore, do not purpose limiting the patent granted hereon otherwise than necessitated by the prior art.

We claim as our invention:

1. In combination with a metal surface roll, a pick-up type of felt for conveying a moist web of paper into contact with said roll and a suction roll having a cushioned surface in pressure relation to said metal surface roll with said felt therebetween to transfer said web of paper to said metal surface roll. 70
2. In combination with a heated metal surface roll, a pick-up type of felt for conveying a moist web of paper into contact with said roll and a suction roll having a cushioned surface in pressure relation to **said** metal surface roll with said felt therebetween to transfer said web of paper to said metal surface roll and to remove water from said web and felt. 75
3. In combination with a metal surface roll, a pick-up type of felt for conveying a moist web of paper into contact with said roll and a rubber covered suction roll in pressure relation to said metal surface roll with said felt therebetween to transfer said web of paper to said metal surface roll. 80
4. In a paper machine of the type including a top felt for transferring a moist web of paper from the forming portion to a heated drying cylinder, a resilient surfaced suction roll urged into pressure relation with said heated drying cylinder with said felt and web therebetween to transfer said web of paper to said drying cylinder and simultaneously withdraw water from said felt and web. 85
5. In a paper machine of the type including a top felt for transferring a moist web of paper from the forming portion to a heated drying cylinder, a perforated rubber covered suction roll urged into pressure relation with said heated drying cylinder with said felt and web therebetween to transfer said web of paper to said drying cylinder and simultaneously withdraw water from said felt and web. 90
6. In combination, a roll having heated metal surface, a suction pressure roll having a cushioned perforated surface urged theretowards and a traveling felt for carrying a moist web into the nip between said rolls into contact with said heated metal surface for transfer thereto. 95
7. In combination, a roll having heated metal surface, a suction pressure roll having a cushioned perforated surface urged theretowards, a traveling felt for carrying a moist web into the nip between said rolls into contact with said heated metal surface for transfer thereto and a stationary suction chamber within said suction pressure roll acting through said perforated surface slightly in advance of said nip to remove water from said felt and web. 100
8. In a Fourdrinier type of Yankee paper machine including a forming portion, a drier drum and a pick-up felt for transferring the web of paper from said forming portion to said drier drum, a suction pressure roll associated with said felt and drier drum to transfer said paper web to the surface of said drier drum. 105
9. In a cylinder type of Yankee paper machine including a cylinder mold, a drier drum and a pick-up felt for transferring the web of paper from said cylinder mold to said drier drum, a suction pressure roll associated with said felt and drier drum to transfer said paper web to the surface of said drier drum. 110
10. In a Harper Fourdrinier paper machine, a suction pressure roll associated with the top felt and a heated cylinder for transferring a web of paper carried by said felt to the surface of said heated cylinder. 115
11. In a Fourdrinier type of Yankee paper machine including a forming portion, a drier drum and a pick-up felt for transferring the web of paper from said forming portion to said drier drum, a suction pressure roll having a perforated rubber covering associated with said felt and drier drum to transfer said paper web to the surface of said drier drum. 120
12. In a Harper Fourdrinier paper machine, a suction pressure roll having a perforated rubber covering associated with the top felt and a heated cylinder for transferring a web of paper carried by said felt to the surface of said heated cylinder. 125
13. The method of making paper, which comprises passing a moist web of paper while adhering to a porous textile surface into contact with a traveling heated metal surface and resiliently pressing said paper web against said metal surface to transfer said web thereto while simultaneously subjecting said web of paper immediately in advance of said contact to suction. 130
14. The method of making light weight paper, which comprises conveying a moist web of light weight paper on a pick-up felt into close proximity to a revolving heated metal surface, resiliently pressing said felt toward said heated surface to bring said paper web into contact therewith for transfer thereto and simultaneously subjecting said felt and web to suction immediately in advance of the contact between said paper web and heated surface. 135
15. The combination with a paper making machine including web-forming means, drying means, a single felt for carrying the web from the forming means to the drying means, and a suction roll for resiliently pressing the web and felt against the surface of the drying means whereby water is removed therefrom and the web transferred to the drying means. 140
16. The combination with a paper making machine including web-forming means, drying means, a single felt for carrying the web 145

from the forming means to the drying means, and a suction roll for pressing the web and felt against the surface of the drying means whereby water is removed therefrom and the web transferred to the drying means.

17. The combination with a paper making machine from which conventional pressing means are omitted, of web forming means, 10 drying means, a single continuous transfer means for carrying the web from the forming means to the drying means, and suction means cooperating with the drying means for transferring the web thereto and for withdrawing water from the web and transfer means.

In testimony whereof, we have hereunto subscribed our names at Beloit, Rock County, Wisconsin.

20   EARL E. BERRY.
